[57] CLAIM

The ornamental design for an endcap, as shown and described.

DESCRIPTION

FIG. 1 is a top, rear, left view of an endcap showing a first embodiment of our new design;

FIG. 2 is a front view thereof;

FIG. 3 is a top plan view thereof;

FIG. 4 is a left side view thereof;

FIG. 5 is a right side view thereof;

FIG. 6 is a rear view thereof; and,

FIG. 7 is a bottom plan view thereof;

FIG. 8 is a top, rear, left view of an endcap showing a second embodiment of our new design;

FIG. 9 is a front view thereof;

FIG. 10 is a top plan view thereof;

FIG. 11 is a left side view thereof;

FIG. 12 is a right side view thereof;

FIG. 13 is a rear view thereof; and,

FIG. 14 is a bottom plan view thereof.
